ABRASIVE WHEEL DRESSING TOOLS

Harry George Teather, London, England, assignor
to Precision Diamond Products Ltd., London,
England, a corporation of Great Britain

Application May 16, 1951, Serial No. 226,555

6 Claims. (Cl. 125—11)

1

This invention relates to abrasive wheel dressing tools and more particularly to a dressing tool comprising a head adapted to be attached to a fixture adjacent the surface of the wheel to be dressed, the head being formed to adjustably support a diamond tipped nib inclined at an angle to the wheel surface.

In the precision grinding and polishing of various metal parts, the abrading wheel must be periodically dressed to true the same to precision accuracy and sharpen the abrading surface thereof. The carbon, boart or ballas (commonly referred to as an industrial diamond) which provides the dressing point for the nib, will obviously wear and develop a flat after continued dressing action. In order that a sharp diamond point or edge is at all times presented for contact with the surface being dressed, it is necessary to periodically rotate or index the nib through a predetermined angle to present a fresh point which has become symmetrically sharpened in previous dressing operations.

Indexing of the nib has heretofore been accomplished, as shown in Jearum's British Patent No. 556,675, by calibrating the tool to indicate a series of equally spaced stations around the nib to which the nib may be indexed in sequence to present a fresh diamond edge or point in working position. Indexing may be effected by rotating the nib to alternate stations so that the indexing distance is double the distance between consecutive stations. By this indexing procedure, a diamond point would be presented at each station when the nib had been rotated through two revolutions.

However, in such indexing, there is constant risk that the operator will inadvertently adjust the nib to an intermediate station, and as a consequence wear the diamond without useful result and produce a poorly and inaccurately dressed wheel surface.

An object of this invention is to provide an improved dressing tool constructed to facilitate the proper indexing of the nib through a sequence of equally spaced stations in alternating order and in a foolproof manner to thereby ensure maximum useful life to the diamond and the dressing of the wheel surface in minimum time to precision accuracy and maximum sharpness.

Other objects and advantages of this invention will become apparent as the disclosure proceeds.

Although the characteristic features of this invention will be particularly pointed out in the claims, the invention itself, and the manner in which it may be carried out, may be better under-

2

stood by referring to the following description taken in connection with the accompanying drawing, in which

Fig. I is a plan view of this improved abrasive wheel dressing tool as it would appear when supported by a fixture and in dressing contact with an abrasive wheel;

Fig. II is a longitudinal cross section of the dressing tool as viewed in the plane of line II—II of Fig. III;

Fig. III is an end elevational view of the dressing tool;

Fig. IV is a transverse cross section of the dressing tool as viewed in the plane of line IV—IV of Fig. II;

Fig. V is another transverse cross section of the dressing tool as viewed in the plane of line V—V of Fig. II;

Fig. VI is a fragmentary transverse cross section of the dressing tool as viewed in the plane of line VI—VI of Fig. II; and

Fig. VII is a plan view of the Allen key used in assembling, adjusting and indexing the dressing tool.

Similar reference characters refer to similar parts throughout the several views of the drawing and the specification.

Referring to the drawing, this improved abrasive wheel dressing tool comprises a head 10 fixed to a shank 12 designed to be mounted in a suitable fixture F to adjustably support a removable diamond tipped nib 30 at an inclined angle to the surface of the abrasive wheel W to be dressed. The supporting fixture F may be constructed to reciprocate the tool nib transversely across the operating surface of the wheel during the dressing operation.

The head 10 may be made in a single piece from cast or shaped metal and presents a solid body section 11. The supporting shank 12 may have a threaded end portion 13 extending into a threaded cavity 14 in the body section 11 and firmly but removably secured thereto by a set screw 15 threaded into the body section 11. The set screw may have a polygonal wrench socket cavity in the end thereof so that it may be manipulated by the polygonal end portion a" of the Allen key as shown in Fig. VII.

The head 10 also presents a nib-containing section 16 having a tubular bore to receive and support the nib 30 on a longitudinal axis extending at an inclined angle of approximately 30° to the longitudinal axis of the supporting shank 12. The nib-containing section 16 presents a main bore 17 of cylindrical form which

terminates at an internal collar portion 18 as shown in Fig. II. The internal collar portion 18 presents a reduced bore 19 which leads into an enlarged open bore cavity 22 of cylindrical form. The internal collar portion 18 thus defines an inner shoulder 20 and an outer shoulder 21. The main bore 17, the reduced bore 19 and the open base cavity 22 are in axial alignment. As shown in Figs. III and IV, the open bore cavity 22 also defines a semi-cylindrical side wall 10 portion 23 whose free edge is notched out to present an entry notch 24 and an exit notch 25 spaced by a raised cam edge 26 whose purpose will be hereafter explained.

The tool head 16 is also provided with a square or polygonal-shaped clamp receiving hole 27 extending through the body section 11 as shown in Figs. II and V. The hole 27 presents one face 28 thereof in intersecting relation to the main bore 17 to define a common rectangular shaped 20 opening 29 therebetween.

The cutting diamond supporting nib 30 may be shaped from a steel rod to present a main body portion 31 of cylindrical form designed to snugly seat within the main bore 17 of the 25 tool head. The cutting diamond 32 is solidly set in the end face 34 of the main body portion of the nib by a selected metal matrix 33. The exposed end face 34 is preferably tapered at an angle of 30° to 45° to adequately expose the cutting tip of the diamond 32 as set therein.

The nib 30 presents a reduced body portion 35 extending from the main body portion 31 to define an inset shoulder 36 and is cylindrically shaped to snugly telescope into the reduced bore 19 of the internal collar portion 18 of the head. The nib 30 terminates in a threaded end portion 37 of reduced diameter to present a second inset shoulder 38 at the point of juncture with the reduced body portion 35. The threaded end portion 37 of the nib is designed to extend through the open bore cavity 22 of the tool head. The threaded end portion 37, the reduced body portion 35 and the main body portion 31 of the nib are axially aligned and as assembled in the head are in axial alignment with the main bore 17, the reduced bore 19 and the open bore cavity 22 of the tool head.

The nib 30 is removably and adjustably locked within the bore of the nib-containing section 16 of the head by a nib lock 40 which comprises a head clamp pad 41 connected to a foot clamp pad 42 by a socket screw 43 as shown in Figs. II and V. The clamp pads 41 and 42 have the same polygonal shape as the receiving hole 27 and are sized to snugly telescope therein. The socket screw 43 has a head portion 44 inset within a conforming cavity in the head clamp pad 41 and is equipped with a polygonal wrench socket for manipulation by the polygonal end a' of the Allen key A. The screw 43 has a threaded shank portion 45 threading into the foot pad 42. Both clamp pads 41 and 42 present inclined nib clamping faces positioned at the rectangular opening 29 to engage the nib body portion 31. By tightening the screw 43, the clamp pads 41 and 42 will grip and hold the nib 30 in adjusted position, and by loosening the screw 43 the nib 30 may be rotated in the bore of the tool head as presently described. The screw 44 presents a circumferential groove 47 to receive spaced indentations or dimples 48, punched into the body of the clamp pad 41 after assembly on the screw head 44, so that the clamp pad

41 may be withdrawn from the hole 27 with the socket screw 43.

An index disc 50 made of metal and designed to snugly fit within the bore cavity 22 of the tool head, is provided with a threaded hole 51 to be threaded onto the threaded end portion 37 of the nib to serve as a nib supporting nut. The index disc 50 is also designed to snugly seat on the outer shoulder 21 of the internal collar portion 18 of the tool head. A series of equally spaced key receiving holes 52 extend radially around the periphery of the index disc 50 and are shaped to receive the cylindrical end a' of the Allen key A. The index disc 50 as shown in Fig. IV is equipped with seven equally spaced socket holes 52 to provide for seven indexing stations. The index disc 50 is capped by a dome-shaped locknut 53 having an internal threaded socket 54 for attachment to the threaded end portion 37 of the nib. The locknut 53 may be provided with diametrically spaced flattened outer faces 55 for wrench application. When the locknut 53 has been tightened, the index disc 50 will seat against the secondary inset shoulder 38 of the nib.

The tapered diamond supporting end of the nib 30 as mounted in the tool head normally projects from the nib-containing section 16 thereof to fully expose the cutting diamond for wheel dressing application. A helical spring 56 is contained within the main bore 17 of the tool head as shown in Fig. II to normally retain the indexing disc seated against the outer shoulder 21 of the internal collar portion 18 of the head. The helical spring 56 is preferably frusto-conical in shape and embraces the reduced body portion 35 of the nib, with its reduced end 57 seating against the primary inset shoulder 36 of the nib. The larger end 58 of the helical spring 56 is designed to seat against a split ring or circlip 63 formed as shown in Figs. II and VI. The circlip 63 is made of spring steel and is tempered to tightly fit within the main bore 17 of the tool head and seat against the adjacent inner shoulder 20 thereof. The ends 64 of the circlip 63 are normally spaced apart, but may be drawn together when inserting and removing the circlip into and from the bore 17 by the provision of grip holes 65 therein to which long-nosed pliers may be applied.

A retaining pin 60 extends through a conforming hole extending through the internal collar portion 18 and presents a head portion 62 which seats under the circlip 63. The retaining pin 60 is designed for vertical movement within the collar hole provided therefor and presents a tapered end portion 61 normally exposed at the surface of the outer shoulder 21. The tapered end portion 61 of the retaining pin 60 is designed to selectively nest within pin sockets 59 formed in the adjacent face of indexing disc 50. Each of the pin sockets 59 is positioned directly adjacent and below each of the socket holes 52 in the index disc 50 as indicated in Fig. IV, and are arranged to cooperate with the spring loaded pin 60 to retain the index disc 50 and the nib 30 in the selected indexed position.

As thus constructed and assembled, the helical spring 56 operates to maintain the index disc 50 resiliently seated against the outer shoulder 21 of the tool head, leaving the operating end of the nib exposed for dressing application to the abrasive wheel. When the point of the diamond 32 has been worn down and flattened by wheel dressing action, the nib 30 is rotated through a

prescribed angle in the tool head so as to present a fresh diamond point for wheel surface contact. This adjustment may be made by first loosening the socket screw 43 with the Allen key A to release the grip exercised by the clamp pads 41 and 42 on the main body portion 17 of the nib. The cylindrical end α' of the Allen key A can then be inserted into that index disc socket hole 52 which is exposed at the entry notch 24 in the tool head as shown in Fig. III. By means of the Allen key, the nib 30 may then be turned to the right as shown in Fig. III by pulling the Allen key over the raised cam edge 26, causing a corresponding telescoping movement of the nib 30 in the bore of the head against the action of the helical spring 56. When the disc turning Allen key reaches the exit notch 25 of the tool head, the helical spring 56 will telescope the nib in the opposite direction to its normal operating position, and the index 50 will again seat against the outer shoulder 21 of the head and there be retained by the spring loaded pin 60. When the second cutting point of the diamond nib is thereafter worn by wheel dressing action so that it no longer dresses with the desired efficiency, a third diamond point may be presented for wheel contact by repeating the adjustment above described.

This improved abrasive wheel dressing tool as illustrated in the accompanying drawing presents seven dressing stations, which may be designated as stations 1 to 7 inclusive as defined by the seven equally spaced peripheral socket holes 52 in the disc 50. However, as shown in Fig. III, only two alternate socket holes 52 are exposed at the entry notch 24 and the exit notch 25 of the tool head, the intermediate socket hole being covered by the intervening raised cam edge 26 of the head. The exit notch 25 in the head is so shaped that the index disc cannot be turned when the Allen key is at the exit notch. Thus, the nib can only be rotated by inserting the Allen key A at the entry notch 24 and then turning the key to the right as shown in Figs. III and IV to the alternate station. When seven operating stations are provided, each to present a fresh diamond point for dressing action, the sequence of station adjustment would be from station 1 to 3, then from station 3 to 5, then from station 5 to 7, then from station 7 to 2, then from station 2 to 4, and finally from station 4 to 6. Thus the nib would be adjustable to seven alternate stations and would make two complete revolutions during the useful life of the diamond.

It will be appreciated, however, that a five station or a seven station or a nine station adjustment of the nib may be provided as desired, by forming a corresponding number of equally spaced key sockets 52 in the index disc 50, and by locating the key entry notch 24, exit notch 25 and intermediate cam edge 26 to accord.

When the diamond set in the nib has been worn after several indexing adjustments until its useful life has been substantially consumed, the nib may be readily removed from the head by loosening the socket screw 43 and then removing the dome-shaped locknut 53 and index disc 50 from the threaded end portion 37 of the nib, thereby permitting complete withdrawal of the nib from the tool head. The used diamond can then be reset or a new cutting diamond bonded to the operating end of the nib.

The indexing features of this improved abrasive wheel dressing tool ensures maximum life to the cutting diamond mounted in the nib thereof, with a sharp diamond point precisely presented for

wheel dressing action. This improved wheel dressing tool is substantially foolproof in use, and is constructed to ensure indexing adjustment of the nib for maximum dressing efficiency without calculated attention or inspection by the operator to determine whether the best diamond point is being presented for wheel dressing action. Thus a fresh sharp point, generated between two flats worn in the previous cycle, is constantly presented to the abrasive wheel without calculated attention, thereby ensuring maximum useful life of the diamond and rapid dressing of the abrasive wheel to maximum sharpness and precision accuracy.

It is understood that this invention may be embodied in various modifications and adaptations and is not limited to the particular embodiments described and illustrated, but that various revisions, substitutions and changes may be made by those skilled in the art.

What is claimed is:

1. An improved abrasive wheel dressing tool including in combination, a tool head having a nib receiving bore, a mounting nib having a body portion telescoping within the bore of the tool head, clamping means set within the tool head for adjustably securing the nib body in the bore of the tool head, an index disc secured to the nib body having a series of equally spaced indexing stations indicated thereon, said tool head having a wall contoured to present a pair of spaced notches designed to expose two alternate indexing stations in said index disc and conceal the remaining indexing stations therein.

2. An improved abrasive wheel dressing tool including in combination, a tool head having a nib receiving bore, a mounting nib having a body portion telescoping within the bore of the tool head, clamping means set within the tool head for adjustably securing the nib body in the bore of the tool head, an index disc secured to the nib body, said index disc having a series of equally spaced indexing sockets each defining an indexing station, said tool head having a wall contoured to present a pair of spaced notches designed to expose two alternate indexing sockets in said index disc and to cover the remaining indexing sockets therein against accessibility except by alternate indexing adjustment of the nib.

3. An improved abrasive wheel dressing tool including in combination, a tool head having a supporting shank and a nib receiving bore whose longitudinal axis is inclined at an angle to the axis of the shank, a mounting nib having a body portion telescoping within the bore of the tool head, clamping means set within the tool head for adjustably securing the nib body therein, an index disc secured to the nib body, said index disc having a series of equally spaced indexing sockets extending around the periphery thereof, said tool head having a wall contoured to present a key entry notch and a key exit notch designed to expose alternate indexing sockets in said index disc to key access and prevent access to the remaining indexing sockets therein except by alternate indexing adjustment of said nib.

4. An improved abrasive wheel dressing tool including in combination, a tool head having a nib receiving bore, a mounting nib having a body portion telescoping within the bore of the tool head, adjustable clamping means set within the tool head for securing the nib body in the bore of the tool head, said bore having a shoulder defined therein, an index disc removably secured to said nib body having indexing sockets equally spaced

around the periphery thereof, resilient means within the bore of the head operative to normally retain said index disc seated against said shoulder, said head having a wall portion surrounding the periphery of said index disc contoured to present a key entry notch and a key exit notch designed to expose a pair of alternate indexing sockets in said index disc, said wall presenting a key camming edge extending between said paired indexing sockets closing the intermediate indexing socket to key access.

5. An improved abrasive wheel dressing tool including in combination, a tool head having a nib receiving bore, a mounting nib having a body portion telescoping within the bore of the tool head, adjustable clamping means set within the tool head for securing the nib body in the bore of the tool head, said bore having an internal collar presenting inner and outer shoulders, an index disc having indexing sockets equally spaced around the periphery thereof, means for removably securing said index disc to the nib body, a helical spring contained within the bore of the head seating between an abutment shoulder formed on the nib body and the inner shoulder of said internal collar and operative to normally retain said index disc seated against the outer shoulder of said internal collar; said head having a wall surrounding the periphery of said index disc contoured to present a key entry notch and a key exit notch exposing a pair of alternate indexing sockets in said index disc, said wall presenting a raised key camming edge extending between said paired notches closing the intermediate and adjacent indexing socket to key access. 20

6. An improved abrasive wheel dressing tool including in combination, a tool head having a supporting shank and a nib receiving bore whose longitudinal axis is inclined at an angle to the axis of the shank, a mounting nib having a body portion telescoping within the bore of the tool head, adjustable clamping means set within the

5
10

tool head for securing the nib body in the bore of the tool head, said bore having an internal collar presenting inner and outer shoulders, an index disc and a locknut threaded to one end of the nib body, said index disc having indexing sockets equally spaced around the periphery thereof, a helical spring contained within the bore of the head embracing a body section of the nib and seating between an abutment shoulder formed on the nib body and the inner shoulder of said internal collar, a lock pin extending through said internal collar operative to fix the indexed position of said disc; said helical spring being operative to normally retain said index disc seated against the outer shoulder of said internal collar; said head having a wall portion surrounding the periphery of said index disc and contoured to present a key entry notch and a key exit notch which expose a pair of alternate indexing sockets in said index disc to key access; said wall portion presenting a raised key camming edge extending between said paired notches and closing the intermediate and adjacent indexing socket to key access. 25
